STOKER

Frank T. Nicholson, Braintree, Mass.

Application April 3, 1937, Serial No. 134,805

10 Claims. (Cl. 221—122)

The present invention relates to stokers for mechanically feeding coal into furnaces, and more particularly to the means for supplying the coal to the stoker.

5 As commonly constructed, these stokers are arranged with a plurality or series of coal feeding units to which the coal is supplied from a single common source, such as a bin or hopper, connections being provided from the bottom of 10 the hopper to each stoker unit. Commonly these bins or hoppers are provided with downwardly converging side and bottom walls, and the connections or "throats" also have converging walls which form a contracting passage for the coal.

15 In such constructions difficulty is often experienced in securing an uninterrupted movement or flow of the coal through such a contracting throat, due to the tendency of the coal to pack and arch over under the weight of the 20 coal and the wedging action of the tapering side walls. While stoppage of the coal supply occurs even when the coal is dry, it is much more likely where the coal is wet or damp, and since it is a common practice to construct these coal supply bins or hoppers in the open with no roof or other shelter, the coal is exposed to rain and 25 snow.

It is the object of the present invention to 30 provide a construction in which such stopping in the movement of the coal from the hopper to the stoker will be avoided and a continuous, uninterrupted supply of coal to each stoker unit will be insured.

To the above ends the present invention contemplates the provision of a connection or throat 35 between the hopper or other source of supply and the stoker units in which an expanding passage for the coal is provided so that the compacting of the coal by the wedging action of the walls 40 of the throat will be prevented and all danger of arching eliminated.

Another feature of the invention is the provision of a connection or throat member of the 45 above type which is adapted to be positioned or inserted in the converging throats of installations already constructed and thereby eliminate liability of interference in the future with the regular supply of coal to the stoker.

50 Still another feature of the present invention is the provision of a stirring device or agitator adjacent the upper or entrance end of the coal passage in the connection or throat, with suitable actuating mechanism to facilitate and insure the passage of coal from the supply into

the expanding passage of the throat or connection.

Other features of the invention will appear in the appended drawings and the following description wherein are shown and described a preferred form of the present invention as applied to an underfeed mechanical stoker of a well known type.

In the accompanying drawings Fig. 1 is a vertical side sectional view taken on line 1—1 of Fig. 2 of only those portions of such a stoker installation as are deemed necessary for an understanding of the present invention; Fig. 2 is a front view of the same, partly in elevation and partly in section; Fig. 3 is a top view, partly 15 in section, on line 3—3 of Fig. 2; Fig. 4 is a vertical side sectional view, on an enlarged scale, of the upper portion of the connection or throat, showing the agitator for the coal; Figs. 5, 6 and 7, are a top plan, a front, and a side elevation, respectively, of the new and improved 20 throat member separate and detached from the other parts; Fig. 8 is a side elevation of a modified form of the same part; and Fig. 9 is a transverse sectional view, on an enlarged scale, of one 25 of the cross-members of the coal agitator.

The stoker, which is shown only in part in the drawings, comprises briefly a series of stoker units extending across the front of the furnace, each unit having a cylinder with a ram therein 30 and a common actuating shaft for reciprocating the ram to feed the coal into the furnaces. An elevated bin or hopper extending across the front of the furnace, with a connection or throat from the bottom of the hopper to each ram cylinder, 35 supplies the coal thereto.

Referring first to those portions of the construction shown in the drawings which are old and well known in the art, these comprise a plurality or series of ram cylinders 11 mounted 40 each opposite an opening 13 in the furnace wall 15. Each cylinder is formed with an opening 17 in its top wall adjacent the furnace, the side walls 18 being extended upwardly and diverging as shown in Fig. 2. The coal is supplied to the 45 cylinder through the opening 17 and then fed by the reciprocations of the ram (not shown), through the passage 13 into the furnace. A ram shaft 19 mounted across the front of the cylinders is rotated slowly from a suitable source of 50 power to impart the feeding and return strokes to the rams of the several units by suitable connections familiar to those skilled in the art, which it is not necessary here to describe.

The coal for the several units of the stoker is 55

supplied from a hopper or bin 21 having the downwardly converging front and rear walls 23 and 25 and extending across the face of the furnace above the stoker units. In these prior constructions the connections or throats and the openings in the ram cylinders were provided with a substantially vertical back wall 27 and downwardly inclined and converging front and side walls 28 and 31, respectively, all four walls fitting into the opening 17 in the top of the ram cylinder, as shown in Figs. 1 and 2.

To provide access to the interior of the connection or throat to loosen the coal in case its downward movement should be prevented by arching 15 or for any other reason, an opening 33 was formed near the bottom of the front wall 28 for a slide or closure 35 removably held in place by the lips or ears 37 on the wall. When the coal became packed or arched over and ceased to flow, the slide 20 would be removed and a poker or suitable implement used to free and loosen the coal.

In order to eliminate this contracting passage or throat with its liability to cause packing and arching of the coal, the connection member described above has been provided, in accordance with the present invention, with an expanding throat or passage so that all compacting and wedging of the coal at this point is prevented. This is accomplished, in the embodiment illustrated in the drawing, by the provision of an additional or supplementary throat member adapted to be positioned in the old converging throat, and provided with an expanding passage for the coal. None of the old parts already installed have to be disturbed, the new throat member being of such a size and shape as to fit within the old throat and be retained in position by its own weight and the weight of the coal above without requiring the use of bolts or other fastening devices.

The preferred form of throat member constructed in accordance with the present invention is shown detached in Figs. 5, 6 and 7, and installed in position in Figs. 1 to 4. It comprises a rectangular flat top 41 of a size to fit within the entrance opening of the old throat, with marginal portions of the top resting upon the curved connecting tops 43 of the old side walls of adjacent throats, (see Fig. 2). The top of the new throat member is provided with an opening or recess 45 of rectangular configuration extending inwardly from the rear edge of the top. Extending downwardly from the bottom face of the top at the edges of the opening 45 are the front wall 47 and the side walls 49, each of which diverges outwardly from the vertical center line of the opening, so that a three-sided expanding passage is formed having a greater cross-sectional area at its bottom than at the top. Triangular supports or webs 51 mutually reinforce and strengthen the top and side walls.

The bottom margins of the side walls are bevelled slightly, as shown at 53, to avoid contact with the lower ends of the side walls of the old throat and with the upper portions of the expanding side walls of the cylinder, which might interfere with the proper seating of the top 41 on the tops of the old throat walls. The front wall of the supplementary throat is provided at its bottom with the opening or recess 55, the inner lower corners of the wall being bevelled, as at 57, to avoid contact with the ram when the latter is reciprocated in the cylinder. On each side of the recess 55 are positioned lips or ears 59 which are undercut on their inner faces adjacent the

wall to receive a closure or gate 61 to close the opening 55. This gate or closure comes opposite the old closure 35 on the original throat construction so that if for any reason it is desired to gain access to the interior of the ram cylinder or to the ram therein, this can be done by removing first the outer closure in the old throat and then the inner closure on the supplementary throat.

Preferably the new and improved supplementary throat or connection will be cast in one piece. While all the intermediate throat members will be identical, separate and slightly different castings would be required for the end sections where one side wall of the old throat was straight, as shown in Fig. 2. For such locations the margin 15 at the top would be of reduced width on one side or the other, as required.

While the three-wall construction shown in Figs. 5 to 7 has been found most satisfactory in actual use, the fourth or back wall of the coal passage being formed by the straight back wall of the old throat, it may be preferred in some locations to use a throat member having four walls completely enclosing the coal passage, with all of the walls diverging. Such construction is shown in Fig. 8.

To insure the continuous flow of coal from the hopper into the upper end of the coal passage in the new throat construction, there has been provided a stirrer or agitator for the coal immediately above the entrance opening, the agitator being actuated from some convenient source of power, preferably the ram shaft. A convenient form of agitator is illustrated in Figs. 1 to 4 of the drawings, and comprises an elongated grid or ladder-like construction which rests upon the aligned tops of the throat members and is slowly reciprocated longitudinally during the operation of the stoker.

As shown in Fig. 3, the agitator comprises the elongated side members 65 and 67 extending the width of the hopper and connected by the spaced transverse or cross-members 69. A convenient form of assembly is by welding the cross-members to the side members which are arranged as best shown in Fig. 4, with the front member positioned flatwise and the rear member edgewise. Shorter intermediate transverse members 71 which extend only part way across from the front side member toward the rear member are welded to the front member only. Preferably the transverse members are of segmental form in cross section, as shown on an enlarged scale in Fig. 9, the bottom face being flat and the top face arcuately convex.

The agitator is reciprocated in the illustrated embodiment of the invention from the continuously rotating ram shaft 19 by the crank 73 mounted on the end thereof, as shown in Fig. 3. The rotary movement of the crank is transferred into reciprocatory motion of the agitator by means of a vertical shaft 75 mounted to oscillate in suitable bearing support 77. Fixed to its lower end is the arm 79 connected by the link or pitman 81 to the crank 73, while at its upper end is secured the arm 83 connected by link 85 to the agitator. Thus as the ram shaft rotates, the agitator is reciprocated back and forth over the top surfaces of the throat members, stirring and loosening the adjacent coal so that a continuous movement of the loose coal into the entrance end of the passage in the throat members is insured.

The convex upper surface of the transverse members tends to maintain the agitator in posi-

tion upon the top surface of the throat members, irrespective of the direction of movement, but to avoid any possibility of the rear member of the agitator rising, the hold-down guides 89 have been provided, (see Figs. 2 and 4), which are welded in position to the back wall at the top of the old throats or connections.

The extent of movement of the agitator is preferably such that the cross-members 68 will traverse substantially the entire distance between adjacent throat openings, but not pass over any part of the openings themselves, while the shorter intermediate members 11 will traverse substantially that portion of the top surface of the throat members lying to the front of the opening. Thus, on each cycle of operation or double stroke of the agitator, substantially the entire flat top surface of each throat member will be traversed, but at no time will the entrance to the passage in the throat member be obstructed or covered by any part of the agitator.

In the operation of the stoker illustrated in the drawings, the coal feeds downwardly in a continuous, slowly moving stream from the hopper or bin through the expanding passages of the throat members into the ram cylinders. As the ram shaft rotates slowly, increments of coal are fed successively from the cylinders into the furnace by the reciprocations of the rams. At the same time, the agitator is moved back and forth adjacent the entrances to the passages of the throat members, maintaining the coal in loose and free condition irrespective of whether it is wet or dry, or what the height or weight of the coal may be in the hopper.

While the present invention has been shown and described as embodied in a construction wherein a separate and detached throat member is first formed and then positioned within the old connection or throat of an installation, the invention in its broader aspects is not to be limited thereto, as it contemplates the provision in the coal supplying means for a stoker of connections having expanding passages for delivering coal to the stoker whereby packing and arching over of the coal with resultant interruption in its movement will be avoided.

Nor is the present invention limited to the specific form and arrangement of the various parts as herein illustrated and described, as these may be varied as the occasion and conditions require within the scope of the language of the appended claims.

Having thus described the invention, what is claimed is:

1. The combination with a hopper for supplying coal to a stoker or the like, connections between the hopper and the stoker having converging, downwardly extending passages, and supplementary devices positioned in said passages, said devices each having a downwardly expanding coal conveying passage to facilitate the movement of coal from the hopper to the stoker.

2. A throat member adapted to be positioned in the downwardly converging throat of a stoker coal supply, said member comprising a top with an opening therethrough and a plurality of diverging, downwardly extending walls forming an expanding passage for the coal with a discharge opening not materially less in cross-sectional area than said throat.

3. A throat member adapted to be positioned in the downwardly converging throat of fuel supply means of a stoker, said member having a passage therethrough for delivering coal from said means

to the stoker, the passage being of greater cross-sectional area at its discharge end than at its inlet end and the discharge end of the member fitting within the discharge end of said throat.

4. A throat member adapted to be positioned within the downwardly converging walls of the fuel supply means of a stoker, said member comprising a substantially flat top with an opening therethrough, walls extending downwardly from the top at the opening and diverging to form an expanding passage for the coal, said diverging walls of the throat member terminating adjacent the termination of the walls of the fuel supply means.

5. A throat member adapted to be positioned within the downwardly converging walls of the fuel supply means of a stoker, said member comprising a substantially flat top with an opening therethrough at one edge, walls extending downwardly from the top at the edges of the opening and diverging to form with one of the walls of the fuel supply means an expanding passage for the coal.

6. A throat member adapted to be positioned in the fuel supplying means for a stoker, said member comprising a flat top having a rectangular opening therein of substantially less area than the top, side walls extending downwardly from the top adjacent the opening to form an expanding downward passage, one of said walls being provided with an opening in the lower portion thereof, and a removable closure therefor.

7. A hopper for supplying coal to a plurality of stoker units or the like, said hopper having a substantially flat bottom with a plurality of spaced openings therethrough, connections from the openings having downwardly expanding passages for the delivery of coal from the hopper to the stoker units, an agitator in the hopper comprising a plurality of longitudinal members, coal agitating cross-members adjacent the flat bottom of the hopper and spaced from one another between the openings, and means adapted to be driven from the stoker for actuating the agitator to cause the cross-members to reciprocate between the openings, leaving said openings free and unobstructed at all times.

8. A hopper for supplying coal to a plurality of stoker units or the like, said hopper having a substantially flat bottom with a plurality of spaced openings therethrough, connections from the openings having downwardly expanding passages for the delivery of coal from the hopper to the stoker units, an agitator in the hopper comprising longitudinal members on opposite sides of the hopper and adjacent the bottom thereof, coal agitating cross-members connected at their ends to said longitudinal members and spaced from one another between the openings, shorter agitating members intermediate the cross-members connected to one of said longitudinal members and terminating short of the openings, and means for actuating the agitator to move the cross-members between the openings.

9. The combination with a stoker for feeding coal to a furnace comprising a ram cylinder with a coal receiving opening in the upper wall thereof and diverging side walls extending upwardly from said opening, of a hopper having downwardly converging side walls connecting with said cylinder walls, and a throat member positioned between said hopper walls with a top extending across the hopper and with an opening through the top, and side walls surrounding the

opening and extending downwardly and diverging and fitting within the said cylinder walls to form a diverging discharge passage having a discharge opening at its lower end not substantially less in the cross-sectional area than the cross-sectional area of the hopper adjacent the cylinder walls.

10. The combination with a hopper for fuel and the like having a bottom discharge opening 10 and side walls adjacent the opening converging

downwardly to form a discharge throat, of a supplementary throat member positioned in the throat of the hopper, said member having a top extending across the throat of the hopper, an inlet opening through the top, and downwardly diverging side walls terminating in a discharge opening positioned within and approximately of the same cross-sectional area as the throat of the hopper.

FRANK T. NICHOLSON. 10
